UNITED STATES PATENT OFFICE.

MERIAN H. DICKINSON, OF SEATTLE, WASHINGTON.

LOADING ENGINE.

Application filed July 20, 1921. Serial No. 486,101.

To all whom it may concern:

Be it known that I, MERIAN H. DICKINSON, a citizen of the United States, residing at Seattle, in the county of King and State of Washington, have invented certain new and useful Improvements in Loading Engines, of which the following is a specification.

My invention more particularly relates to a loading device comprising a plurality of motors or engines for loading the logs, and is particularly applicable where two such engines are used.

My invention will best be understood by reference to the accompanying drawings in which I have illustrated a preferred embodiment of my invention, and in which Figure 1 is a diagrammatic view in side elevation illustrating a skidding system, and a loading system embodying my invention; Fig. 2 is a plan view thereof; Fig. 3 is a side view of the loading device; Fig. 4 is a plan view thereof; Fig. 5 is a longitudinal section through the steam cylinder and associated parts for releasing the clutch mechanism of one of the loading engines; Fig. 6 is a plan view, partially broken away to show certain parts in section of the control lever; Fig. 7 is a longitudinal section through the loading drum and associated parts of one of the engines, and Fig. 8 is a longitudinal sectional view of the drum and associated parts of the other engine.

Like reference character indicate like parts in the various figures.

Referring, now, to the drawings, and first to Figs. 1 and 2, 10 is a main supporting cable passing over a sheave or sheaves 11 secured to the head spar or tower 12, it being understood that the cable 10 is anchored at its opposite ends. The head spar or tower 12 is preferably held in position by guys 12^a in the usual manner. A skidding carriage 13 is movable along the supporting cable 10 and is moved in one direction by an outhaul cable 14 connected to the carriage, as at 15, it being understood that the cable passes over a sheave at the tail tower, or other point of support (not shown), and returning passes over a sheave 16 on the head spar and is wound on a drum 17 of the skidding engine, the skidding engine being indicated in general at 18. A skidding line 19 passes over a sheave 20 pivotally connected to the skidding carriage 13, as indicated in Fig. 1, and also passes over a sheave 21 attached to the

head spar, the skidding line being wound upon a drum 22 of the skidding engine. The skidding line is shown attached to a plurality of logs 23 which are being dragged from a distant point to a position where they may be loaded. A slack-pulling cable 24 passes over a sheave 25 on the skidding carriage and is attached to the skidding line, as at 26, in a well-known manner. The slack-pulling cable passes over a sheave 27 on the head spar and is wound upon a drum 28 of the skidding engine. The skidding system described above which is used for hauling the logs from a distant point to the position where they are to be loaded, as on a flat car, is well known and constitutes no part of my present invention.

In accordance with my invention, loading cables 29 and 30 pass over sheaves 31 and 32 pivotally connected to loading carriages 33 and 34, the loading cables being provided at their ends with hooks 35, or other attaching means, which may be secured at separated points to the ends of a log or other load on opposite sides of the center of gravity thereof. I have illustrated the loading operation being carried out with logs, one of which is indicated at 23^a in a position to be lowered onto a flat car 36, the wheels of which engage the track rails 37 of a track 38. The loading carriages 33 and 34 are supported on cables 39 attached at one end to the head spar, as at 39^a, and at the opposite end to anchors 39^b and 39^c, as illustrated in Fig. 1, the carriages being properly spaced apart to permit the ends of the loading lines to be connected to a log or other load. The carriages 33 and 34 are fixed in position by guys 33^a and 34^a, which are also anchored to the ground, and prevent the carriages traversing the cables toward the head spar, the weight of the cables and connecting parts on the carriage being sufficient to prevent their moving in the opposite direction, toward the ground. The loading cables 29 and 30 pass over sheaves 40 and 41 on the head spar, and are wound upon drums 42 and 43 of the loading engine.

I will now describe the operating connections and control of the drums 42 and 43, it being premised that these drums are operated by separate engines and are separately controlled.

Referring, now, particularly to Figs. 3 and 4, in which I have illustrated steam en-

gines as the preferred form of power means for operating the loading cables; the drum 42 is loosely mounted on a shaft 44 having its bearings at 45 in the bed-frame 46. The 5 drum 42 is mounted adjacent to a gear wheel 47 secured on the shaft 44 and is normally held in frictional engagement therewith, so that the gear and the drum rotate together by means which will be more 10 fully described hereinafter. The gear 47 engages a driving pinion 48 secured on a shaft 49, which has its bearings in the frame 46. Crank discs 50 are preferably secured to either end of the shaft 49 and are provided with crank pins 51 which are connected to cylinders 52 of one of the loading engines or motors A through suitable connections, which I have indicated at 53 by dotted lines. The engine A is controlled by a 15 manually operated lever 54 which is pivotally mounted for vertical movement on a shaft 55. I have illustrated at 54^a a second lever for controlling the second engine by connection, which will be later described. 20 The parts associated therewith are similar to those associated with the lever 54, and are indicated by the same reference characters with the letter *a* appended, and certain of the parts which will now be described are 25 illustrated more clearly in connection with the lever 54^a than are those in connection with the lever 54, and reference should be made thereto. The lever 54 is preferably bolted, as at 56, to a casting 57, which is 30 provided with upper and lower plates 58 (see Fig. 3), embracing a sleeve 59, which surrounds the shaft 55, having its bearings at 60, in a standard or bracket 61. The plates 58 are secured to the collar 59 by 35 pins 62, indicated in dotted lines in Fig. 6, so that the collar 59 is rotated by the vertical rotation of the lever 54; at the same time the plates 58 are pivoted on the pins 62 so that the lever 54 may be moved laterally and has, in effect, universal movement, the movements of the lever in one 40 plane being utilized to control motive power to the motor and in another plane to control the slip connections between the associated motor and the load. An arm 63 is 45 attached to the collar 59 and is preferably formed integral therewith, as indicated in Fig. 6. One end of a link 64 is pivoted, as at 65, to the end of the arm 63, and the 50 other end of the link 64 is pivoted at 66 to an arm 67 which is secured to a shaft 68 having its bearings in a standard 69. To the shaft 68 is also secured an arm 70 to 55 which is pivoted, as at 71, one end of a link 72, the opposite end of which is pivoted at 73 to an arm 74 secured on a shaft 75 having its bearings in the frame and extending to the opposite side of the engine, as indicated in Fig. 4. At an intermediate point 60 of the shaft 75 is secured an arm 76, to the

outer end of which is pivoted a stem 77 which extends upwardly into the valve chest 78 and controls the admission of steam through the pipes 79 to the cylinders 52 in a well-known manner. The movement of the lever 54 preferably controls the admission of steam in the following manner: When the lever 54 is raised above its horizontal position steam is admitted to the cylinders 52 to produce forward movement of the engine and raise the load. When the lever is moved to the horizontal position, steam is cut off from the cylinders 52, and when the lever is moved below the horizontal position, the engine is reversed to lower its load.

In accordance with my invention, slip connections are preferably interposed between each engine and its associated drum, and provision is made for releasing these connections more or less, so that the load on either of the drums may be lowered without positively driving the engine. This control is preferably effected by the same levers which control the engines themselves. In the embodiment here shown, the casting or member 57 is provided with a laterally projecting arm 80 which forms with the lever a bell-crank so that a lateral movement of the lever 54 will move the arm 80 forwardly or backwardly. To the end of the arm 80 is pivoted a link 81, the opposite end of which is pivoted to an arm 82 secured on a shaft 83. To the opposite end of the shaft 83 is secured an arm 84 to which is pivoted, as at 85, one end of a link 86, the opposite end of which is pivoted at 87 to an arm 88 secured on a shaft 89 having its bearings in the frame and extending across the engine, as indicated in Fig. 4. To the opposite end of a shaft 89 is secured an arm 90, as indicated in Fig. 4, which is pivoted at 91 to a link 92, the opposite end of which is pivoted at 93 to an arm 94 secured on a shaft 95 having its bearings in the casing 96 of the valve chest, as indicated in Fig. 5, the shaft passing through the valve chest. To the shaft 95 is secured within the valve chest a mutilated gear 97 which engages a rack 98 formed on the slide valve 99 which controls the admission and exhaust of steam to the steam cylinder 100 in the usual manner, and the connections for which need not be specifically described. A piston 101 in the steam cylinder is connected by a piston rod 102 to a cross-head 103, which is, in turn, connected by two connecting rods 104 to an arm 105 secured on a shaft 106, so that the reciprocation of the piston rocks the shaft 106. Preferably a dash-pot, indicated in general at 107, is provided for controlling the speed of operation of the piston. For this purpose a cylinder 108 is provided which is preferably filled with oil, and within which is a piston 109 connected by a stem

110 to the cross-head 103. A by-pass pipe 111 is preferably provided and is nippled at 112 and 113 to the respective ends of the cylinder 108. The by-pass pipe 111 is provided with a valve 114 for controlling the flow of liquid through the by-pass and thereby controlling the dash-pot effect of the cylinder 107.

The rocking of the shaft 106 effects the release of a slip connection between the drum 42 and the gear 47 by mechanism the preferred form of which will now be described.

To the shaft 106 is secured an arm 115 (see Fig. 3), to the outer end of which is pivoted, as at 116, a link 117, the other end of which is pivoted at 118 to an arm 119 (indicated in dotted lines in Fig. 3), which is secured to the head 120 of a screw 121 (see Fig. 7) received in a screw threaded opening 122 in the frame. The inner end of the screw engages, as at 123, the end of a rod 124 extending axially through the shaft 44 on which is loosely mounted the loading drum 42. The opposite end of the rod 124 engages a key 125 passing through a slot 126 with which the shaft 44 is provided. The key 125 in turn engages a collar 127 surrounding the shaft, the opposite edge of the collar 127 engaging a ring 128 loosely surrounding the shaft, which in turn engages a stiff coil spring 129, which is placed under compression between the ring 128 and a collar 130 spaced from the ring 128 and adjustably secured to the shaft 44. The collar 130 is preferably provided with a sleeve 131 of smaller external diameter which may be integral therewith, and which surrounds the shaft 44 and forms a seat for the spring 129. The ring 128 overlaps the collar 127 and the inner portion of the drum 42. One of the flanges 132 of the drum is preferably provided with a laterally extending flange 133, which forms on its interior at 134 a frictional engagement with a corresponding flange 135, secured to, or integral with, a plate 136, which is in turn secured to the gear wheel 47 secured on the shaft 44. Normally, the spring 129 forces the drum 42, through the collar 128, into engagement with the gear wheel 47 with sufficient force to ensure the drum being rotated by the gear wheel. When the described control mechanism forces the stem 124 to the left, as viewed in Fig. 7, and compresses the spring 129 in the manner described, the frictional engagement between the drum and the gear wheel is lessened, and the load, such as the log, may thereby be lowered by the slipping of the drum with reference to the gear wheel. I have illustrated in Fig. 7 a "spotting" drum 137 which may be used for moving cars. This drum is preferably provided with a flange 138 which forms frictional engagement at 139 with the gear wheel 47. Normally the frictional connection is dis-

engaged by a spring 140 interposed between the spotting drum and the gear wheel, but which may be compressed by a manually operated lever 141 to bring the spotting drum into engagement with the gear wheel 70 and thus actuate the drum 137. It will be understood that the cable wound on the drum 137 is connected to cars for the purpose of moving them along the track. It will also be understood that the spotting 75 operation and loading operation are not carried on simultaneously and that when the spotting operation is to be carried on then the loading drum 42 is disconnected from the gear.

The frictional engagement between the drum 42 and the gear 47 may readily be adjusted by moving the collar 130 longitudinally of the shaft and thus compressing to a greater or less extent the spring 129. The 85 collar 130 may be adjusted conveniently by means of a screw 142 similar to the screw 121, the inner end of the screw engaging the rod 143 extending longitudinally through the shaft and engaging a key 144 extending 90 transversely through a slot 145 in the shaft 44. The key 144 engages the collar 130 and the movement of the key produces a corresponding movement of the collar.

The drum 43 on which the loading line 30 95 is wound is operated by a separate engine and is controlled in a manner similar to the drum 42, and the mechanism and control for this drum will now be briefly described. A second manually operated lever 54^a, which 100 is preferably adjacent the lever 54, so that both levers may be actuated by one operator, is mounted for universal movement on the shaft 55^a in the same manner as the shaft 54. To the arm 63^a is pivoted a link 146, the opposite end of which is pivoted at 147 to an arm 148 secured on a shaft 149 extending across the engine, as indicated in Fig. 4, and having its bearings in the frame of the machine. On the shaft 149 is secured an arm 110 150 to which is pivoted at 151 a link 154, the opposite end of which is pivoted at 155 to an arm 156, which is in turn secured to a shaft 157 having its bearings in the frame 115 of the machine. On the shaft 157 is secured an arm 158, the outer end of which is pivoted at 159 to a stem 160 which extends upwardly into the valve chest 161 and controls the admission of steam through the pipes 162 to the cylinders 163 of the engine B. The 120 cylinders 163 are connected at 164 to the crank pins 165 of crank discs 166 on the opposite ends of the shaft 167 having its bearings in the frame 46. On the shaft 167 is secured a pinion 168 meshing with a gear 125 wheel 169 secured on the shaft 170 and having its bearings in the frame 46 and on which is also loosely mounted the drum 43. The vertical movement of the lever 54^a controls the operation of the engine B and of 130

the drum 43 in the same manner that the lever 54 controls the drum 42, and need not further be described.

To the arm 80^a on the casting 57^a is connected a link 171, the opposite end of which is pivoted at 172 to an arm 173 secured on a shaft 174, having its bearings in the frame. To the shaft 174 is also secured an arm 175, pivoted at 176, to one end of a link 177, the opposite end of which is pivoted at 178 to an arm 179 which is secured to a shaft 180 passing through the valve casing 181 and controlling the piston within a cylinder 182 in precisely the same manner as the cylinder 100, and the connections from the piston of which need not be more specifically described. The operation of the piston rocks a shaft 183 (see Fig. 4) having its bearings in blocks 184 of the frame. To the shaft 183 is secured an arm 185 to which is pivoted at 186 a link 187, the opposite end of which is pivoted at 188 to an arm 189 which rocks a screw 190 in the same manner that the screw 121 in Fig. 7 was rocked. The inner end of 25 the screw 190 engages a rod 191 extending axially through the shaft 170, the opposite end of the rod 191 engaging a key 192, which in turn engages a collar 193, and this collar in turn engages a collar 194 which releases 30 the spring 195 and thereby disengages the friction clutch connection between the drum 43 and the gear 169, in precisely the same manner as in the case of the drum 42 and the gear 47. The specific arrangement of the 35 slip connection between the engines and the drums 42 and 43 and the control therefor is not claimed herein, as I am not the first inventor thereof, the same being the invention of Thomas Spencer Miller, of South Orange, 40 New Jersey. The spotting drum 137 may be controlled by a foot lever 197 secured on a shaft 198, the rotation of which by the foot lever 197 applies a friction band 199 to the flange 138 of the drum 137 in a well known manner.

The operation of the loading device embodying my invention will readily be understood from the foregoing description, and is as follows:

50 When the device is used for loading logs, as illustrated in the drawings, the logs will usually be hauled to the point where they are to be loaded by a skidding arrangement which may be the same as that described. 55 The hooks 35 on the loading cables 29 and 30 are then attached to a log 23^a. The operator then raises the levers 54 and 54^a thereby applying steam pressure to both engines A and B to produce forward movement thereof and haul in the loading cables and raise the log to the position indicated in Fig. 1. In 60 case the load is light, or for other reasons it is desired to lower the load by steam pressure, the operator depresses the levers 54 and 54^a below the horizontal positions,

thereby reversing the engines A and B and causing the steam engines to rotate positively the drums 42 and 43 on which the loading cables are wound in a direction to pay out the cables. Ordinarily, however, it is desirable to lower the cables without use of steam pressure, and in accordance with my invention this is accomplished by releasing the slip connections between the two engines and their associated drums in the described manner, the slip connections permitting the load to be lowered. By suitably manipulating the levers 54 and 54^a, as by moving them laterally and moving them back to their original positions, more or less steam may be admitted to the cylinders 100 to produce more or less movement of the pistons 101 therein, and thereby control the amount of friction in the slip connections so that the speed of the lowering operation may be controlled. The speed at which the load may be lowered may further be controlled by the valve 114 which controls the by-pass for the fluid in the cylinder 107.

By the provision of the mechanism for permitting the slipping connection between the loading drums and the gears with which they are associated, the logs may be lowered at a much greater speed than where they are lowered by the steam engine, as is usually the case. Furthermore, they are lowered without wasting steam and without the wear and tear on the engine that would result when the engines are used for lowering the load.

What I claim and desire to secure by Letters Patent of the United States is:

1. In an engine, a winding drum, a motor for operating the same, a slip connection interposed between said motor and said drum, a manually operable member movable in different planes, means responsive to the movement of said member in one plane for controlling the energy supply to said motor, and means responsive to the movement of said member in a different plane for controlling said slip connection.

2. In a log loading device, two independent motors, separate means operated by the respective motors and adapted to be simultaneously connected to a log at opposite sides of the center of gravity thereof, separate control means for the respective motors, independent slip connections interposed between each motor and the connections for the log for lowering the log, and manually operable members operable in different planes, each member operable in one plane for controlling the movement of the associated motor in either direction and in another plane for controlling the slip connections.

3. In a log loading device, two independent motors, separate means operated by the respective motors and adapted to be simul-

aneously connected to a log at opposite sides of the center of gravity thereof, separate control means for the respective motors, independent slip connections interposed between each motor and the connections for the log for lowering the log, and manually operable members adjacently located and accessible to a single operator and operable

in different planes, each member operable in one plane for controlling the movement of the associated motor in either direction and in another plane for controlling the slip connections.

In testimony whereof I have hereunto signed my name.

MERIAN H. DICKINSON.
